Primary Examiner — Nathan M Johnston(74) *Attorney, Agent, or Firm* — Baker Botts L.P.(57) **CLAIM**

The ornamental design for a portable dehumidifier, as shown and described.

DESCRIPTION

FIG. 1 is a perspective view of a portable dehumidifier showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof;

FIG. 9 is another perspective view thereof;

FIG. 10 is an enhanced perspective view of the indicated portions of the portable dehumidifier of FIG. 1;

FIG. 11 is another enhanced perspective view of the indicated portions of the portable dehumidifier of FIG. 1; and, FIG. 12 is another enhanced perspective view of the indicated portions of the portable dehumidifier of FIG. 1.

The broken lines show portions of the design that form no part of the claimed design.
